UNITED STATES PATENT OFFICE.

CHARLES CRISTADORO, OF ST. PAUL, MINNESOTA.

DOVETAIL-MORTISING MACHINE.

SPECIFICATION forming part of Letters Patent No. 552,351, dated December 31, 1895.

Application filed July 15, 1892. Serial No. 440,135. (No model.)

To all whom it may concern:

Be it known that I, CHARLES CRISTADORO, of St. Paul, Ramsey county, Minnesota, have invented certain Improvements in Dovetail-
5 Mortising Machines, of which the following
is a specification.

My invention relates to improvements in
machines designed to cut mortises in the ends
10 of the sides of box-boards to receive corre-
sponding tenons upon the end boards of the
box, its object being to provide an improved
machine adapted to cut a series of mortises
in a plurality of boards in one operation.

To this end my invention consists in provid-
15 ing a gang of cutters adapted to cut straight
grooves with parallel sides in the stock as
passed over them. Arranged to travel past
these bits is the slideable frame or clamp hav-
20 ing rocking angle-blocks on opposite sides, be-
tween which the boards are placed and held
at the same angle with the path of the cutters
as the desired dovetail angle of the mortise
25 to be cut. When thus placed, the boards are
clamped and held firmly in position so that
the grooves cut may be absolutely unvarying.
The first part of the operation being com-
pleted, which consists of the cutting of the
30 series of grooves with the travel of the stock
over the cutters, the clamp is loosened and the
angle-blocks reversed so as to turn and hold
the stock at an exactly opposite angle, the
35 clamp being again tightened. The frame or ta-
ble is provided with shifting devices whereby
the frame with its load can be moved laterally
to compensate for the variation between the
40 positions of the grooves first cut in the boards,
with the path of the cutters, so that on the
reverse movement of the stock in the second
part of the operation the cutters will enter
45 the throats or adjacent ends of the grooves
cut in each board and cut away one of the
side walls of the grooves so as to shape them
into the required dovetail form.

My invention further consists in the specific
50 construction and combination hereinafter de-
scribed, and particularly pointed out in the
claims.

In the accompanying drawings, forming
part of this specification, Figure 1 repre-
55 sents a plan view of my device, showing the
position of the clamping-frame in which the
stock is held in relation to the cutters, and

the clamping attachments therefor, and the
means for shifting the frame laterally. Fig.
2 is a side elevation of the same. Fig. 3 is a 55
plan view of the clamping-frame, one posi-
tion of the stock being indicated by full lines
and the reverse position by dotted lines, and
Figs. 4, 5, 6, and 7, respectively, illustrate
diagrammatically the position of the stock 60
when adjusted to receive its first cut, its po-
sition when tilted to the opposite angle, its
position when laterally shifted to bring the
openings of the grooves cut by the first oper-
ation into line with the cutters, and the form 65
of the mortises cut by the two operations
therein.

In the drawings, 2 represents the bed of
the machine, upon which the table A is ar-
ranged to slide laterally in suitable guides 3. 70
At the sides of the table are arranged the
stops 4 and 5 limiting its lateral movement.
The lever 6, pivoted to the bed of the ma-
chine and connected by the link 7 to the ta-
ble, serves to move the same laterally between 75
the stops, as hereinafter described. Mounted
upon the table A to slide longitudinally of the
machine is the frame B. The clamp-screw
8 provided with the hand-wheel 9, mounted
upon the table A and threaded into the table 80
B, serves to drive the table B along the frame
A in the operation of the machine. Upon the
table B is mounted the clamping-frame C, con-
sisting preferably of the side bar 10 and the
end pieces 11 rigidly secured to and formed 85
integral with the bar 10 and at right angles
therewith. The bar or frame-piece 12, par-
allel with the piece 10, slides on guides 13 to
and from the piece 10, so as to vary the width
of the frame, the springs 14 between the mem- 90
bers tending to throw the movable piece 12
outward. Pivoted securely to the members 10
and 12 at or near their centers are the rocking
angle-blocks 15 in the form of isosceles trian-
gles, the equal angles of which correspond to 95
the angle of the dovetail to be cut in the stock.
Between these blocks are placed boards or
pieces of stock 16 which are firmly secured in
the required angular position by means of the
eccentric roll or cylinder 17, arranged parallel 100
with the bar 12 and provided with the handle
18, by means of which it may be turned in its
bearings to crowd the bar 12 inward against
the tension of the springs and firmly clamp the

stock between the blocks. In order to hold the stock in contact with one of the end pieces or bars 11, so that the notches or mortises cut therein shall be at exactly the same distance from the edge of all the boards, I arrange a set-screw 19 in one of the end frame-pieces adapted to bear upon the follower 20, arranged transversely in the frame and bearing upon the sides of the stock, thus pressing them against the opposite end of the frame and holding them in contact with it. Arranged in suitable bearings (not shown) upon the machine are the series of cutters 21, which project upward through the slotted openings 22 in the table B, so as to be brought in contact with the stock held in the frame C and cut a series of grooves in the stock as it is carried by the table B over them.

In Figs. 4, 5, 6, and 7 are illustrated the different positions of the stock in relation to the cutters and the work done by them therein. Fig. 4 illustrates the position of the stock to receive the first cut, the angular position being indicated by the dotted lines in Fig. 3. The paths of the cutters 21 are indicated by the dot-and-dash lines, and with the first part of the operation the straight grooves 23 are cut through the series of boards, which, being placed at an angle with the plane of the cutters, the grooves cut are at the same angle through them. After the first cut the lever 18 is turned to release the clamp and the set-screw 19 loosened, when the angle-blocks may be rocked, carrying the stock into the position illustrated in Fig. 5. It is evident that the openings or ends of the notches on the sides of the boards toward the cutters will then be out of alignment with them, and the stock must consequently be moved laterally to bring them into alignment, which adjusted position is illustrated in Fig. 6. The stock being then carried past the cutters, they cut away one wall of the notches in the boards, as indicated

by the dot-and-dash lines, thus forming the dovetail notches 24, as shown clearly in detail Fig. 8, adapted to receive corresponding tenons on the outer box-boards.

I claim—

1. The combination with the series of groove cutters, of means for presenting a plurality of pieces of stock to said cutters whereby a series of parallel grooves is cut in the edges of the stock, means for shifting all of said stock to a predetermined angle with its first position, for shifting each piece laterally with reference to the adjacent pieces, and for laterally shifting the position of all the stock with reference to the cutters, whereby in presenting the same a second time to said cutters one side of the grooves in the several pieces of stock is cut away to form similar dovetail notches, substantially as described.

2. The combination with the series of groove cutters, of means for holding a plurality of pieces of stock at a predetermined angle with the path of the cutters, means for shifting said angle a predetermined degree, means for uniformly shifting the several pieces of stock laterally with reference to each other a predetermined distance, means for laterally shifting all of the stock a predetermined distance, and means for presenting said stock to said cutters, substantially as described.

3. The combination with the clamp, of the angle blocks respectively pivoted to the members of the clamp and adapted to be set to hold the stock in either of two similar but opposite angular positions, and the follower and its screw adapted to hold the stock against one end of said clamp, substantially as described.

In testimony whereof I have hereunto set my hand this 11th day of July, 1892.

CHARLES CRISTADORO.

In presence of—

T. D. MERWIN,
H. S. JOHNSON.
